UNITED STATES PATENT OFFICE.

HENRY EVANS STAMPELEY, OF SIBLEY, LOUISIANA.

GLARESHIELD.

Application filed January 4, 1926. Serial No. 79,166.

This invention relates to glare shields.

The object is to provide a simple device which may be readily attached on an automobile, and quickly and easily operated by the driver of the car to shut out the glaring headlights of approaching automobiles, and which may be locked to remain in such position while driving after dark, or be easily permitted to automatically return to normal position between times if desired or during day driving, in which normal position, the shield offers no interference to the full view of the road from side to side by the driver of the car.

Another object is to provide a device of this character which will not detract from the appearance of the car, requiring no material alteration in the same, and which is capable of ornamentation to attract attention if desired, the operating means for shifting the position of the shield being located close to the corner post in an out-of-the-way position so as not to interfere with the steering of the car, and yet within easy reach of the left hand of the driver to be actuated while still guiding the car with the other hand.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a side elevation showing the device in applied position, on a closed car.

Figure 2 is a top plan view of the same, portions of the car being shown in section.

Figures 3, 4, 5 and 6 are details of the construction, drawn on an enlarged scale.

Figure 7 is a detail horizontal section similar to Fig. 2 and showing the manner of mounting the device on an open car.

The invention comprises a supporting bracket 1, formed of metal and of light construction, the same having an attaching base

portion 2 which is suitably apertured for the reception of fastening screws to attach the same to the front face of the corner post 3 of an automobile, it being understood that 60 the post 3 may be either the corner structure of a closed car or the corresponding upright bar of an open car, as the invention may be used to equal advantage on either type of car.

Adjacent to the front end of the horizontally disposed arm 4 of the bracket 1 is a centrally disposed, upstanding pivotal post or bolt 5, and at the terminal of said arm, there are provided upstanding lugs 6 spaced 70 apart and adapted to act as stop lugs in a manner to be explained.

Pivotedly mounted on the bracket is an elongated plate 7, preferably formed of suitable sheet metal, though some other 75 opaque material may be employed, said plate constituting the adjustable shield element of the device, the same being mounted to partake of a slight sidewise movement at its front end inwardly towards the longitudinal 80 center line of the hood of the automobile to contact with the inner lug 6 when travelling at night to shield the eyes of the driver from the glare of approaching headlights.

To this end, the rear edge of the plate is 85 provided with an eye 8 which is adapted to receive the pivotal post or bolt 5, the head of the bolt serving to retain the plate in position to freely revolve on the bolt, and the latter being held in position by a nut 9. 90 The rear end of the plate having the eye 8 formed therein, is preferably of less height than the front portion thereof, as shown at 10, and a horse or other figure 11 may be formed of the sheet metal on the upper edge 95 of this reduced rear portion, if desired, to serve as an ornament and also to allow a vision between the legs or other portions thereof, the forward or higher portion of the plate acting to entirely screen the said glare 100 from the driver's vision, when the approaching car is yet in advance of him, and permitting of a momentary glimpse of the lights, through said space, as they flash past, thus allowing the driver to keep his 105 eyes on the right side of the road exclusively, without visual interference, enabling him to avoid running off the road.

The device is attached to the corner post 3 at a suitable elevation to accord with the 110 level of the particular owner's or driver's eyes, so that the longitudinal center line of

the forward portion of the shield is substantially on said level and said portion, when the plate is swung to the position indicated in dotted lines at A in Figure 2 of the drawing, by means to be described, it will be seen that the driver may freely see straight ahead of him and carefully watch his side of the road and yet, when the approaching car has reached what may be termed the danger zone, say a hundred feet or so in advance, the forward portion of the shield effectually screens the annoying headlights until they safely pass, when a momentary view of the same may be had through the said space at the rear end of the plate, to notify the driver of said passage.

The front end of the plate 7 is further provided with a vertical eye 12 in the intermediate portion of which there is pivoted the looped end 13 of a pull rod 14 which passes rearwardly through a sleeve 15 set into the corner post 3 in horizontal alignment with the hinged, front end of the rod, and at the rear end, the latter is provided with a downturned handle 16 in rear of the wind shield and within easy reach of the driver of the car.

The passageway through the sleeve 15 is of a diameter to permit the rod to partake of the necessary rocking action in deflecting the plate 7, as indicated in Figure 2, and the said rod is preferably widened where traversing the sleeve, as shown in Figure 3, and is provided in its upper edge with spaced notches 17 for engagement with a pivoted latch 18, which may be lifted from one notch and which will gravitate into the other notch to lock the rod in its forward or rearward positions.

The plate 7 is provided on its outer face with an ear 19 extending outwardly and having a perforation for the hooked end of a coiled spring 20, which extends slightly outward towards its rear end and which is hooked into a perforated ear 21 outstanding from the outer side edge of the horizontal portion of the bracket 4 and at the front end thereof to exert a constant outward pressure on the plate against the outer stop lug 6, as clearly shown in Figure 5 of the drawing.

The upper end of the eye 12 formed at the front end of the plate 7 is adapted to receive the staff of a small flag or banner or other ornamental device if desired, and it will be seen, from the foregoing, that a simple, cheaply manufactured and strong and durable device for shielding the eyes of automobile drivers from glaring headlights, has been provided, which may be easily installed in position to suit the requirements of the individual driver, and which may be readily shifted by him to eliminate the annoyance and danger of said lights, without interfering with his driving, or with his vision straight ahead, or with his side of the road,

the constant strain of the spring on one side of the plate and the locked engagement of the pull rod on the other side thereof, serving at all times to hold the shield plate 7 rigidly in position against one or the other of the lugs 6 to resist the pressure of the wind.

In Figure 7 the bracket 1 is shown attached, as by suitable screws, to the side post 3 of the top supporting frame of an open car. There is ample space between said post and the frame of the windshield 3^b for the actuating rod 14 to operate in, and the pivoted latch 18 may be carried by an attaching plate of bracket 18^a suitably held in proper position on the said post 3^a and having an extension 18^b provided with a guide opening of proper size to guide the rod 14 and permit same to be moved forwardly and rearwardly when said latch is lifted from its engagement in the notches 17 of the rod.

What is claimed is:—

1. A glare shield for automobiles comprising a vertically disposed rigid plate located in front of the wind shield and normally extending longitudinally of the car, a supporting bracket adapted to be secured to the corner post of the car and to extend forwardly in advance of the driver, a vertical pivoting post carried by the front end of said bracket for pivotal connection with the rear end of the plate, means for swinging the front end of the plate inwardly towards the longitudinal center line of the hood of the car to obscure approaching headlights, and stops carried by the bracket for limiting the inward and outward swinging movement of the plate.

2. A glare shield for automobiles comprising an elongated plate formed of opaque material and having a vertical pivotal eye at one end, a bracket adapted to be secured to the front of the top supporting post at the driver's side of the car and to extend forwardly therefrom, an upstanding pivotal post carried near the front end of the bracket and traversing the eye of the plate to pivotally support the same in advance thereof, a pull rod pivotally connected to the front end of the plate and passing rearwardly through the post and terminating in a handle within the car for swinging the plate at a slight angle across the car for shielding the driver's eyes from approaching headlights.

3. A shield for protecting automobile drivers' eyes from approaching headlights, comprising an elongated plate of opaque material, a support carried by the corner post of the car and extending forwardly, means for pivoting the plate at its rear end on the front end of the support, said plate normally extending in longitudinal alignment with the same and with the car, spaced

stop lugs formed on the front end of the support to stop the plate in exact longitudinal alinement or in an angular position across the car, a pull rod flexibly connected to the plate and extending to the driver to move said plate to the latter position, means for locking the rod in its extreme positions, and a coiled spring terminally connected to the support and the plate to pull the latter to the former or normal position when the pull rod is released.

4. A glare shield for automobile drivers' eyes, comprising a supporting bracket secured to the corner post of the car and extending forwardly in front of the same, a shield plate pivoted thereto for horizontal swinging, a coiled spring for returning the plate to longitudinal alinement, a pull rod

connected to the plate for swinging the same to an angular position relative to the car, spaced lugs carried by the bracket to limit the movement of the plate, said pull rod extending through said corner post and terminating in a handle and having spaced notches formed therein, and a latch pivoted to the post and adapted to engage in the notches to lock the glare shield in either longitudinal alinement with the car when not endangered by approaching headlights or in a slightly angular position to obscure headlights and permit full view of the right side of the road.

In testimony that I claim the foregoing as my own, I have hereto affixed my signature.

HENRY EVANS STAMPLEY.
